UNITED STATES PATENT OFFICE.

SAMUEL TURNER AND THOMAS EASTAUGH, OF ROCHDALE, ENGLAND, ASSIGNEES TO
SAMUEL TURNER & COMPANY, LIMITED, OF SPOTLAND, ROCHDALE, ENGLAND.

LOOM FOR WEAVING.

Application filed September 26, 1928, Serial No. 308,895, and in Great Britain July 2, 1927.

This invention relates to looms for weaving with more particular reference to those which are fitted with automatic weft replenishing mechanism, and has for its object to 5 provide improved means for cutting the tag ends at the cloth selvedge.

The invention consists in apparatus for this purpose comprising a clamp for holding the tag ends and scissors mechanism for 10 cutting the same so arranged that the clamp operates just before the scissors come into operation.

The accompanying drawings illustrate one mode of carrying out the invention:—

15 Figure 1 is a more or less diagrammatic plan showing a part of the breast beam of a loom with parts mounted and arranged thereon in accordance with the invention;

20 Figure 2 is a sectional elevation of a part of the clamp and scissors mechanism according to the invention, and

Figure 3 is a side elevation of the whole mechanism.

In carrying our invention into effect we 25 may apply our improvements to existing looms or to looms specially built for the purpose, and such looms are provided with the usual accessories incidental to weft replenishing looms, that is to say, with some 30 form of magazine (not shown) for the cops and with a transerrer *a* on a hammer shaft *b* for the purpose of pushing a full cop into the shuttle and simultaneously ejecting therefrom the empty cop whenever the weft 35 requires replenishing.

We may also provide the usual weft fork and hammer mechanism (not shown) for bringing into operation the weft replenishing means such as is commonly employed on 40 automatic weft replenishing looms.

For the purpose of cutting the tag ends of the cloth selvedge we provide a clamp *t²*, pivoted at *s²* (Figures 1 and 3) for holding 45 in conjunction with the upper prong of the fork member *u* such ends and a scissors mechanism *t³* pivoted at *s³* for cutting the same, but our arrangement differs from those hitherto adopted in that the clamp and scissors levers (which may both be operated 50 simultaneously by a cam-operated or other arm or like device *t⁴*) are so fulcrumed (as clearly seen in Figure 2) that the clamp will

come into operation to hold the thread between it and the upper prong of member *u* before the scissors mechanism so that the 55 weft end is firmly held before it is to be cut and thus the cutting operation can at all times be successfully accomplished.

The clamp and scissors may be opened by means of an arm *t⁵* (Figure 3) mounted on 60 the shaft *e'*.

It will be understood that the invention is not to be limited to the foregoing details of construction which are given by way of example only, nor is it to be limited to any particular type or construction of loom to which it is to be applied while at the same time it will be evident that many of the improvements hereinbefore described such, for example, as the temple and temple cutter, 65 shuttle thresher, means for lubricating the loom spindle, and means for adjusting the same, may be applied with equal effect and like advantage to any ordinary construction 70 of loom and are not to be limited in their 75 application to weft replenishing looms.

Having now described our invention, what we claim as new and desire to secure by Letters Patent is:—

1. In a weft replenishing loom for weaving, a fulcrumed clamp for holding the tag ends of the cloth and a fulcrumed scissors for cutting said tag ends, a single operating element, the clamp and scissors including lever arms positioned to be engaged simultaneously by the single operating element, the fulcra of the clamp and scissors being so arranged that the clamp operates before the scissors. 80

2. In a weft replenishing loom for weaving, a clamp and scissors mechanism, each including a fixed member and a movable lever arm, a single operating element for simultaneously engaging the ends of the movable lever arms, the fulcra of the arms 95 being located at different distances from the operating element whereby the clamp operates to hold the tag ends before the scissors cut the same. 95

In testimony whereof we have signed our 100 names to this specification.

SAMUEL TURNER.
THOMAS EASTAUGH.
